UNITED STATES PATENT OFFICE.

ROLLO W. BROWNE, OF WASHINGTON, DISTRICT OF COLUMBIA.

HERNIAL TRUSS.

SPECIFICATION forming part of Letters Patent No. 655,601, dated August 7, 1900.

Application filed February 3, 1900. Serial No. 3,856. (No model.)

To all whom it may concern:

Be it known that I, ROLLO W. BROWNE, a citizen of the United States, residing at Washington, in the District of Columbia, have invented certain new and useful Improvements in Trusses; and I do hereby declare the following to be a full, clear, and exact description of the invention, such as will enable others skilled in the art to which it appertains to make and use the same.

The present invention is designed as an improvement on that class of truss-pads wherein is employed a yielding hollow pad, preferably air-distended, the pad being constructed with a convex contact-face formed by an elastic pliable wall, a rigid flat rear wall formed by a double thickness of rubber, and a flat metal plate located within and of about the same diameter as the said wall, the rubber being cast around and completely inclosing the said plate, thereby permanently and rigidly securing the same within the rear wall, and one or more screws or lugs extending from the outer portion of the rear wall and secured to or formed with the plate, the convex face and the rear wall being by preference cast integral. While such pad is of great efficiency in use and has thoroughly and effectively filled a long-felt want, yet it has been found in practice that there is a feature inherent to such pad that renders it objectionable to some users, arising from the fact that the contact-face of the pad being of rubber will, under the action of heat due to use, emit a disagreeable odor, consequent upon perspiration and secretions from the body of the wearer.

It is the object of the present invention to overcome this objection in a simple and effective manner by providing such contact-face with a metallic shield or cover which shall be non-corrosive in character and of such flexibility as to obviate any discomfort in the use of the pad, such shield being adapted to yield independently of the pad proper—that is to say, being so assembled with relation to the pad that when the latter yields the shield will also yield, but in an independent manner, so that an ease and comfort in use will be assured that could not result if the metallic shield were firmly attached to the pad.

With this object in view the invention con-

sists, broadly, in the combination, with a yielding pad, of a shield, of non-corrosive metal conforming to the pad.

55

The invention consists, further, in the combination, with a yielding pad, of a shield made of non-corrosive metal conforming to the pad, but disconnected therefrom.

The invention consists, further, in the combination, with a yielding pad, of a metallic shield inclosing the contact-face of the pad and adapted to yield independently of the pad.

The invention consists, finally, in the novel construction and combination of parts of a truss-pad, as will be hereinafter fully described and claimed.

In the accompanying drawings, forming a part of this specification, and in which like letters of reference indicate corresponding parts, I have illustrated a form of embodiment of my invention, it being understood that the same may be varied without departing from the spirit thereof.

75

In the drawings, Figure 1 is a view in elevation of the pad. Fig. 2 is a view in plan. Fig. 3 is a view in vertical longitudinal section, showing the arrangement of the different parts of the pad.

80

Referring to the drawings, A designates the pad, consisting of a convex face a^1 and a rear flat wall or back a^2 , the face and back being by preference formed integral. The pad must be yielding and, as shown, hollow and preferably air-distended. The rear wall a^2 is a multiply structure preferably constructed of two thicknesses of rubber vulcanized together, between which is arranged a metallic plate a^3 , to which the screws or other holding devices 85 from the truss-spring (not shown) may be secured, all of which is old.

90

Entirely surrounding the face of the pad is a shield a^4 , preferably of the contour of the pad and constructed of any suitable non-corrosive metal, by preference of aluminium on account of its lightness and the facility with which it may be stamped or molded. The shield may be formed in any suitable manner, as by being struck up from a die of the 95 shape of the pad, and has its edge inturned to form a flange to rest against the rear wall adjacent to its edge, as shown at a^5 . The shield and pad are disconnected, so that when

100

pressure is applied to the pad the same will yield, and the shield will also yield, but independently of the pad.

Secured to the rear wall of the pad is a plate 5 a^6 , of the same shape as the rear wall and constructed, preferably, of rubber, the plate being slightly larger than the said wall, whereby to present a surrounding flange a^7 , the inner surface of the perimeter of the plate a^6 10 being incut, as at a^8 , to present a channel in which the flange a^5 of the shield may work or move when pressure is applied to the pad. The plate a^6 is secured in any suitable manner to the rear wall, as by being vulcanized 15 thereto, or it may be held in place by the screws or rivets a^9 , which are secured to the plate a^8 and which serve to hold the truss-spring in place.

The channel a^8 , which entirely surrounds 20 the rear wall of the pad, also provides a means by which any accumulation of moisture, either upon the exposed surface of the pad or between the under surface of the shield and the pad, may be caught and removed, thereby 25 presenting a clean and thoroughly-sanitary device.

By the employment of the metallic shield, as described, the objection urged against the employment of rubber, due to its odor, will 30 be entirely overcome.

Having thus fully described my invention, what I claim as new, and desire to secure by Letters Patent, is—

1. The combination with a yielding pad having a peripheral channel, of a metallic shield 35 inclosing the convex face of the pad and provided with a flange engaging the channel, substantially as described.

2. A truss-pad comprising a hollow, permanently-inflated structure, the rear wall of 40 which is provided with a metallic plate, a metallic shield inclosing the convex face of the pad, and having its edge turned and bearing against the rear wall of the pad, and a plate slightly larger, circumferentially, than 45 the rear of the pad, between which and the rear wall of the pad the flange of the shield may work, substantially as described.

3. A truss-pad comprising a hollow, permanently-inflated structure, the rear wall of 50 which is provided with a metallic plate, a metallic shield inclosing the convex face of the pad, and having its edge turned and bearing against the rear wall of the pad, and a plate slightly larger, circumferentially, than 55 the rear of the pad, and having its inner face channeled out to provide space in which the flange of the shield may work, substantially as described.

In testimony whereof I affix my signature 60 in the presence of two subscribing witnesses.

ROLLO W. BROWNE.
